UNITED STATES PATENT OFFICE.

JOSEPH W. PUTNAM, OF NEW ORLEANS, LOUISIANA.

TRUNK-STRAP.

SPECIFICATION forming part of Letters Patent No. 276,466, dated April 24, 1883.

Application filed October 2, 1882. (No model.)

To all whom it may concern:

Be it known that I, JOSEPH W. PUTNAM, of New Orleans, in the parish of Orleans and State of Louisiana, have invented a new and useful Improvement in Trunk-Straps; and I do hereby declare that the following is a full, clear, and exact description of the same, reference being had to the accompanying drawings, forming part of this specification.

10 The object of my invention is to provide an improved strap for fastening down the lid of trunks to prevent them from being burst open from the rough handling which they receive during transportation; and to this end it consists in the peculiar construction and arrangement of the strap, forming a new article of manufacture, as hereinafter fully described.

Figure 1 is a view of the strap applied to the trunk, and Fig. 2 is a perspective view of 20 the strap itself when detached.

A represents the body portion of the strap which passes around the trunk. This portion is made of fibrous woven webbing of heavy thickness and from one and a half to two inches 25 in width. One end of this webbing is secured to a ring, C, and the other end passes loosely through or is looped in another ring, C', and is then doubled back upon itself and attached to a buckle-frame, B, which slips upon the 30 body portion of the strap. To one of the rings, C, a leather thong, D, is permanently attached.

Now, when the strap is to be applied to the trunk the buckle-frame B is adjusted so as to take up or lengthen the body portion of the 35 strap, according to the size of the trunk, and bring the two rings C C' within five or six inches of each other after the strap is around

the trunk. The leather thong is then laced through the two rings with several folds or convolutions, and then by pulling upon the 40 end of the thong the rings are drawn together by an action similar to a block-and-tackle movement, and the strap tightened about the trunk, so as to firmly and securely hold itself in place. The end of the thong is then tied, 45 as shown, or secured in any other suitable manner.

Now, I am aware that trunk-straps made entirely of leather have heretofore been used, and that the separate features of my invention 50 are not new in themselves.

The advantages of my strap, as a new article of manufacture, may be found in its adjustability to any size trunk, and also in the combination of the woven webbing and the leather 55 thong, the webbing serving to clamp the trunk more tightly without scarring it, and not being liable to become stiff and difficult to manipulate from being wet, as is the case with leather, the thong serving also to make a secure and always ready connection for the two ends.

Having thus described my invention, what I claim as new is—

As an improved article of manufacture, a 65 trunk-strap composed of a body-section, A, of fibrous woven webbing, with double or looped end, having adjustable buckle-frame B, rings C C', and leather thong D, as shown and described.

JOSEPH W. PUTNAM.
